[57] CLAIM

The ornamental design for a table top, as shown and described.

DESCRIPTION

FIG. 1 is a top plan view showing my new design;

FIG. 2 is a side elevation;

FIG. 3 is a sectional view taken along lines 3—3 of FIG. 1; and

FIG. 4 is a bottom plan view.

The tread pattern partially shown along the outer periphery of FIGS. 1 and 2 is continuous throughout.

FIG. 1

FIG. 2
